UNITED STATES PATENT OFFICE

GEORGE H. MAGRATH, OF WHITINSVILLE, MASSACHUSETTS

BOBBIN CLUTCH

Application filed July 25, 1928. Serial No. 295,212.

This invention relates to a clutch for securing a bobbin or other weft carrier on a spinning or twisting spindle.

It is the object of my present invention to provide a clutch which shall be yieldingly self-centering, which will accommodate itself to slight variations in the diameter of the bobbin recess, which may be easily and economically manufactured, and which comprises very few and simple parts which may be readily assembled.

My invention further relates to arrangements and combinations of parts which will be hereinafter described and more particularly pointed out in the appended claims.

A preferred form of the invention is shown in the drawings in which

Fig. 1 is a side elevation of a spindle having my improved bobbin clutch applied thereto;

Fig. 2 is a sectional plan view, taken along the line 2—2 in Fig. 1;

Figs. 3 and 4 are sectional elevations, taken along the lines 3—3 and 4—4 respectively in Fig. 2;

Fig. 5 is a plan view of the blank from which the resilient portion of my improved clutch is formed, and

Figs. 6 and 7 are sectional elevations, taken along the lines 6—6 and 7—7 in Fig. 5.

Referring to the drawings, I have shown a spindle having a blade 10 and whirl 11 on which a bobbin B is mounted. The whirl 11 has a recess 12 in its upper face for a purpose to be described.

A cap or casing member 14 is mounted on the blade 10 at a substantial distance above the whirl 11. A spring member, indicated generally by the letter S, is seated in the recess 12 and has the upper end of its spring fingers engaging the head 14.

The spring member S is preferably formed from a single blank of resilient sheet metal, such as spring steel, the blank being clearly shown in Fig. 5 and comprising a band portion 20 from which project centering fingers 21 and driving fingers 22.

The fingers 21 and 22 are bent or offset to the outlines shown in Figs. 6 and 7, while the member S is still in the form of a flat

blank. The band 20 is then bent into a circular outline and of a size to fit snugly into the recess 12 of the whirl 11. When thus positioned, the centering fingers 21 will extend straight upward substantially parallel to the axis of the spindle, as indicated in Fig. 4, and the offset upper end 25 of each finger 21 will be received in a groove 26 in the lower face of the cap 14, the groove being of such radius as to hold the fingers 21 parallel to the spindle.

The driving fingers 22 are somewhat shorter than the fingers 21 and the offset upper ends 28 of the fingers 22 do not extend into the groove 26, but engage a flange 30 formed at the lower end of the cap 14 by recessing the cap, as indicated at 31. The fingers 22 are sprung outwardly and are held under spring tension by the flange 30.

It will thus appear that my improved bobbin clutch comprises only the cap 14 and the spring member S, and that there are no movable parts except the spring centering fingers 22, which have a slight swinging movement at their upper ends.

When a bobbin is placed on the spindle, as indicated in Fig. 1, the driving fingers 22 are forced yieldingly inward and the bobbin is centered by the fingers 21 and band 20, as well as by the head 14. The driving fingers 22 yieldingly engage the inner wall of the bobbin and form effective driving contact therewith.

A bobbin clutch thus formed has no parts capable of displacement or mal-adjustment, and this bobbin clutch is found particularly well adapted for the purposes intended. The smooth outer faces of the fingers 21 and 22 make it easy to dislodge and remove bunches of yarn wound thereon.

Having thus described my invention and the advantages thereof, I do not wish to be limited to the details herein disclosed, otherwise than as set forth in the claims, but what I claim is:—

1. A bobbin clutch for a spindle having a blade and whirl, said clutch comprising a cap mounted on said blade and having a recess and an annular groove in its lower face, a bobbin driving and centering member

comprising a band seated on said whirl and two sets of up-standing fingers alternately disposed on said band, one set of fingers being effective to center the bobbin and having 5 their upper offset ends seated in said annular groove, and the other set of fingers being effective to drive the bobbin and having their upper offset ends yieldingly but unobstructably movable inward in said recess but limited as to outward movement 10 by the peripheral flange of said recess, and means on said whirl to center said band thereon.

2. A bobbin clutch for a spindle having a 15 blade and whirl, said clutch comprising a plurality of alternately disposed resilient centering and driving members mounted on said spindle and positioned for yielding engagement with the inner surface of a bobbin 20 mounted on the spindle, said centering members being held from radial movement at their upper ends, and said driving members being yieldingly but unobstructedly movable inwardly at their upper ends when a bobbin 25 is mounted thereon, and the lower ends of all of said members being joined together and being seated on said spindle whirl, and said whirl having provision thereon to center said members at their lower seated ends.

3. In a bobbin clutch, a resilient member 30 comprising an annular band, and bobbin centering and bobbin driving fingers upstanding from said band and alternately disposed, all of said fingers having inwardly offset upper 35 ends and said centering fingers being longer than said driving fingers.

In testimony whereof I have hereunto affixed my signature.

GEORGE H. MAGRATH.
